CLAIM

(21) Appl. No.: **29/774,110**

The ornamental design for a teeth whitening equipment, as shown and described.

(22) Filed: **Mar. 15, 2021**

DESCRIPTION

(51) **LOC (13) Cl.** **24-02**

FIG. 1 is a right rear top perspective view of a teeth whitening equipment, showing my new design;

(52) **U.S. Cl.**

FIG. 2 is a left front bottom perspective view thereof;

USPC **D24/176**

FIG. 3 is a front elevation view thereof;

(58) **Field of Classification Search**

FIG. 4 is a rear elevation view thereof;

USPC D24/176-178, 107, 152

FIG. 5 is a left side elevation view thereof;

CPC A61C 19/066; A61C 19/063; A61C 17/20;

FIG. 6 is a right side elevation view thereof;

A61N 5/0603; A61N 2005/0606

FIG. 7 is a top plan view thereof;

See application file for complete search history.

FIG. 8 is a bottom plan view thereof;

(56) **References Cited**

FIG. 9 is an enlarged view of a portion labelled, "FIG. 9" in FIG. 2; and,

U.S. PATENT DOCUMENTS

FIG. 10 is another perspective view of the teeth whitening equipment, shown in an alternative position.
